USPTO Notice of Allowance, U.S. Appl. No. 29/688,760, dated Dec. 17, 2021.

Primary Examiner — Cynthia M. Chin

(57) **CLAIM**

The ornamental design for a component of a block game, as shown and described.

DESCRIPTION

FIG. 1 is a perspective view of a component of a block game showing our new design;

FIG. 2 is a front-side elevational view thereof;

FIG. 3 is a back-side elevational view thereof;

FIG. 4 is a left-side elevational view, the right-side elevational view being a mirror image thereof;

FIG. 5 is a perspective view thereof in an environment of use; and,

FIG. 6 is an exploded perspective view thereof in the environment of use.

The broken lines in the figures show portions of the design that form no part of the claimed design and/or are for environmental purposes.

1 Claim, 6 Drawing Sheets(56)
